UNITED STATES PATENT OFFICE.

JOSEPH B. HOLDEN, OF SYRACUSE, NEW YORK, ASSIGNOR TO REMINGTON TYPE-WRITER COMPANY, OF ILION, NEW YORK, A CORPORATION OF NEW YORK.

TYPEWRITING MACHINE.

Application filed October 15, 1919. Serial No. 330,747.

To all whom it may concern:

Be it known that I, JOSEPH B. HOLDEN, citizen of the United States, and resident of Syracuse, in the county of Onondaga and State of New York, have invented certain new and useful Improvements in Type-writing Machines, of which the following is a specification.

My invention relates to typewriting machines and especially to typewriters of that sort which are intended to be readily portable. When a typewriter is carried about there is danger of injury to and perhaps breakage of parts of the escapement mechanism due to the fact that the carriage may be set in such position that the weight of the carriage comes on the feed dogs and the machine may also receive jolts or blows, the force of which would come against said feed dogs.

My invention has for its principal object to insure that the escapement mechanism is disconnected when the machine is prepared for transportation so that the weight of the carriage does not come on the feed dogs. My invention also has other objects which will appear hereinafter.

To the above and other ends my invention consists in certain features of construction and combinations and arrangements of parts all of which will be fully set forth herein and particularly pointed out in the claims.

One embodiment of my invention is illustrated in the accompanying drawings, in which—

Figure 1 is a transverse cross section of the machine taken a little in front of the carriage on line $x-x$ of Fig. 5 and showing the machine enclosed in a carrying case.

Figure 2 is a view of the left-hand end of the carriage and associated parts and shows the mechanism in condition for transportation.

Figure 3 is a view similar to a portion of Fig. 2 but with parts omitted and one part in section and shows the mechanism in position for use.

Figure 4 is an end elevation of the right-hand end of the carriage with parts in section.

Figure 5 is a front to rear vertical sectional view of the machine enclosed in its carrying case but with parts of the machine

shown in broken lines in the positions they occupy when the machine is out of the case and is in condition for use.

In the drawings many parts of the machine are omitted and parts are broken away or shown in section as has been found convenient.

The machine shown in the drawings is of the general sort shown in the patent to Arthur W. Smith, No. 1,342,513 dated June 8, 1920.

The type action, carriage, case shift mechanism, etc., are or may be substantially like those shown in the patent to John H. Barr, No. 1,320,034 dated October 28, 1919, but as far as my invention is concerned the major part of the machine can be constructed in many different ways.

The machine shown in the drawings is a top strike typewriter capable of being compacted or reduced in dimensions in order to be put into a comparatively small carrying case and said machine is made of as light construction as is consistent with the necessary strength and durability.

The main frame of the machine comprises sheet metal side plates 1, Fig. 5, which at their forward ends are rigidly connected together by a transverse frame bar 2, which frame bar constitutes a sort of double comb plate, being slotted both along its upper and along its lower edges for co-operation with parts of the type action. Near their rear ends the frame plates 1 are rigidly connected by means of a casting 3, which may have the general form shown in the applications of Smith and Barr above referred to, and the middle part of which consists, at the rear, of a type bar segment 4, and, at the front, of a sublever segment 5. A comb plate 6, consisting of an angular bar of sheet metal slotted along its lower edge and supporting a wire 7, is secured to the under side of the casting 3 and serves as a pivot bar for key levers 8 having printing keys 9 at their forward ends. Said key levers are guided in the slots in the lower edge of the comb plate 2 and they are connected by links 10 with sublevers 11 pivoted in the slots in the upper edge of said comb plate 2 where they are retained in place by a guard plate 12. Said sublevers 11 are of varying lengths, the one shown being near the middle

100
105

of the machine and one of the shortest in the machine, those near the sides of the system projecting considerably further toward the rear. Each of said sublevers 11 is connected by a link 13 with the free end of a sublever 14. All of said levers 14 are pivoted in radial slots in the sublever segment 5 on a pivot wire 15 and at their rear ends they carry gear teeth meshing with suitable teeth 16 on the heels of type bars 16 which are pivoted on a wire 17 in radial slots in the type bar segment 4. The segments 4 and 5 are arc-shaped as viewed from the top of the machine, and the types on the type bars 16 are adapted to strike down on the upper side of a platen 18. Said platen is mounted in a carriage which so far as my invention is concerned can be of any suitable sort. As here shown the main member of it is a bar 20 bent at its front and rear edges to form two ball bearing raceways, the balls 21 of which run in grooves in rails 22 which rails are mounted on rearwardly projecting brackets 23 which can be supported in any suitable way. In the machine actually being described these brackets are parts of the case shift frame by which the carriage can be shifted front and rear to cause either of the two types on each type bar to print. As this case shift mechanism forms no part of my present invention I have not shown it further than to indicate a bracket 24 secured to the bracket 23 and connected by a link 25 with the stationary framework, the shifting of the frame and carriage being permitted by the rocking of said link 25.

The carriage comprises a left-hand end bracket 26 and a right-hand end bracket 27 in which the platen 18 is mounted. These brackets in light machines of the sort under consideration are preferably of sheet metal and at the right-hand side of Fig. 1 I have shown one of them in section to indicate the manner adopted in the present instance for journaling a platen axle in the brackets. A flanged or headed thimble 28 is inserted through a suitable opening in the upper part of the bracket 27 and a washer 30 is riveted or staked on to the projecting end of the thimble, the construction being such that the bracket 27 is clamped between the head of the thimble and the washer, and said thimble has a hole through it for the platen axle, thus providing a bearing of sufficient length to be serviceable. The construction at the left-hand end of the platen is similar, 28 indicating the head of the thimble, and 30 the washer, in that instance. But the head of the thimble is made a little larger and a little longer for reasons which will presently appear.

The platen as here shown comprises a wooden core 31 and rubber sheath 32, the core having a hole extending longitudinally and centrally thereof. At the right-hand

end of the platen there is a metal fixture or escutcheon 33 having a hub 34 extending into a suitable counter-bore in the wooden core 31, and said escutcheon is fastened to the wooden core by screws 35. There is a somewhat similar structure at the left-hand end of the platen, but at that end there is also a line space wheel 36 fastened to the escutcheon 37. A platen axle 38 extends entirely through the platen and passes through round holes in the escutcheon 37 at the left-hand end of the platen and through the thimble 28 at that end of the platen so that as far as the left-hand end of the platen is concerned the axle is capable of sliding lengthwise of the platen. At its right-hand end the axle 38 is flattened off, at 40, the flattening in the present instance being on three sides, bringing the shaft to a triangular cross section and the outer end of the hub 34 has a hole through it that just fits this triangular shaft so that the shaft can slide through the escutcheon 33 but cannot turn relatively thereto. The triangular part 40 terminates in shoulders 41 which by striking against the end of the counter bore in the hub 34 limits the extent to which the shaft can slide toward the right. A finger wheel or twirler 42 is secured on the right-hand end of the shaft 38 by means of a screw 43. It will be perceived that the construction is such that the platen can be turned by means of the finger wheel 42 and that said finger wheel can be moved a limited distance toward the right and left; that is to say, the shaft can be pushed into the platen to bring the finger wheel to its telescoped or contracted position shown in full lines in Fig. 1 and it can be pulled out to an extended position shown in broken lines in Fig. 1. In assembling the machine, the shaft can be inserted from the left and the finger wheel put on after it is in place.

At the left-hand end of the carriage on the outside of the bracket 26 a bell crank 110 having an upright arm 44 and a forwardly extending arm 45, is pivoted on a screw or stud 46 to the face of the bracket 26. At its upper end the bell crank 44, 45 has bent off therefrom a small handle 47. Any suitable spring 48 tends to lift the arm 45 and to move the arm 44 toward the rear of the machine. Said arm 44 lies in a slot 50 cut vertically in the front face of the head of the thimble 28, said slot being as here shown cut about half-way through said head as indicated in Figs. 2 and 3. When the finger wheel 42 is pushed in as shown in full lines in Fig. 1 the end of the shaft 38 projects outward beyond the thimble 28 as shown and in this position the arm 44 of the bell crank presses against the shaft 38 and is by said shaft held in its forward position against the pressure of the spring 48 and the horizontal arm of said bell crank is held

- depressed as shown in Fig. 2. When the finger wheel is pulled out to its broken line position shown in Fig. 1, which is the position it occupies when the machine is in use, 5 the end of the shaft 38 is drawn in just beyond the arm 44, which arm therefore is by the spring 48 pressed back to the bottom of the slot 50 as shown in Fig. 3 and the horizontal arm of the bell crank moves 10 upward. Said horizontal arm of the bell crank lies over a leftward prolongation of the carriage feed rack 52 which feed rack is mounted on the forward ends of arms 53 which arms are pivoted at their rear ends 15 at 51 on the carriage bar 20. The construction and mounting of said rack 52 are such that it can move up and down to a limited extent and it is normally held up by small coiled springs 54 compressed beneath the 20 arms 53. It will be perceived that the construction is such that the finger wheel 42 cannot be pushed in without first pulling forward on the arm 44 and that when said finger wheel is pushed in the bell crank 25 occupies its rocked position shown in Fig. 2 and the feed rack is depressed against the pressure of its springs 54. It will also be perceived that when the finger wheel 42 is pulled out to its broken line position the bell crank 44, 45 is moved by its spring 48 to its Fig. 3 position and the feed rack 52 is elevated to its normal operative position by its springs 54. At this time the arm 44 lies part way across the end of shaft 38 and 30 locks it and the finger wheel 42 in their outer position, or position of use.
- The rack 52 has teeth on its upper edge which cooperate with any suitable feed dogs 55 mounted on a dog rocker 56 which 40 in turn is mounted on a transverse rock shaft 57 constituting part of the carriage feed mechanism of the machine. Said shaft 57 is controlled in any suitable way by any suitable universal bar 58, the shaft itself and the universal bar being preferably mounted on the case shift frame before referred to. In the present instance the universal bar is carried at its ends on levers 59 which operate arms 69 on the rock shaft 57. It will be perceived that normally the rack 52 engages the feed dogs 55 but that before the finger wheel 42 can be pushed into its position for transportation said rack is depressed out of engagement with 55 the feed dogs and is held down as long as said finger wheel occupies that position.
- The carrying case for the machine can be variously constructed. The one shown 60 comprises a base part 60 and an upper part 61, said parts having a general rectangular form as seen from above. A strip of sheet metal 62 is secured around the inner part of the base 60 and projects above the edge of said base, as shown, thus constituting a flange about which the upper part 61 of the case fits when the case is closed as shown. Said upper part may also have a strip 63 of sheet metal around it for stiffening purposes. Brackets 64 may be secured to the rear wall of the base 60 and project over the base part 65 of the typewriting machine to retain said machine in place in the case, and any suitable means can be provided for holding the front part of the machine. The dimensions of the case 60, 61 in a right and left-hand direction are such that, as will be perceived by inspection of Fig. 1, the machine cannot be put into the case and the cover 61 closed down about it while the finger wheel 42 is in its outer position shown in broken lines. The user of the machine is therefore compelled before he can put it into the case to push the finger wheel 42 to its inner position and he cannot do that without first releasing the carriage from its escapement mechanism.
- In order to insure that the carriage shall be positioned at the right point to make it go into the case properly and in order to hold the carriage when the escapement mechanism is released, any suitable carriage lock can be provided. In the one here shown a slot 66, Fig. 1, is cut through the forward raceway of the carriage bar 20 near the right-hand end thereof and when the carriage is in the correct position for putting into the case said slot matches or registers with another slot 67, Fig. 4, cut in the stationary rail 22. A locking lever 68 is pivoted against the outer face of the carriage bracket 27 on a screw 70 and said lever is bent first toward the left and thence toward the front of the machine and thence downwardly, its free end 71 being adapted to pass into the two registering slots 66 and 67 to lock the carriage to the rail. The lever 68 is prolonged toward the rear to make a handle 72 by which it can be manipulated and its motion is limited in one direction by the washer 30 and in the other by any suitable stop 73. When said handle is moved down against stop 73, the part 71 of the lock is moved out of the slot 67, and the carriage is thus unlocked. The locking lever is held in either of its two positions by friction. There is no danger that the operator will forget to use this lock because if he does by the time he gets the twirler 42 in its compacted position the carriage will be freed of its escapement devices and if left to itself will be driven by its spring to the extreme leftward limit of its travel and this fact would remind the operator to push it back to its proper place and lock it.
- Some of the parts of the typewriting machine shown in the drawing but not heretofore described, will be briefly referred to. In said machine the main frame comprising side plates 1, front bar 2 and casting 3 is

supplemented by and enclosed in a casing 74 which preferably is made of sheet metal in any suitable way and of which the base 65 hereinbefore referred to constitutes a part. A top plate 75 is mounted on the upper part of the casing 74 or on the side plates 1 and it has a depressed middle part in which the type bars 16 lie when the machine is in its compacted condition of non-use and ready for transportation as shown in full lines in Fig. 5. Said type bars rest against a segmental pad 76 which is mounted in a plate here shown as made up of several pieces but generally designated as 77, and means are provided whereby this plate can be dropped down to the position shown in full lines in Fig. 5, in order to compact the machine and whereby said plate and the pad 76 can be raised to the position shown in broken lines in Fig. 5 where it holds said type bars ready to be operated. Said means are fully shown and described in the patent to Arthur W. Smith, No. 1,342,513, hereinbefore referred to. It will be observed that in the machine shown there are two things that have been done in order to get the machine into the carrying case, namely, the plate 77 has to be dropped down in order to compact the type bars and the finger wheel 42 has to be pushed in. It will be understood that the means for insuring that the escapement is released might theoretically be associated with either of these compacting movements or for that matter with any other compacting movement, but I prefer the connection shown, namely, that with the finger wheel, as being simpler than the other. So far as I am aware it is broadly new to connect the carriage release device with a compacting movement of any kind in such a way that the machine cannot be compacted to put it into its case without taking the pressure of the carriage off from its escapement.

45 The case 60, 61, may have its two parts connected together in any suitable way. A hasp or latch 78 is shown in Fig. 5 secured to the front of the cover 61 and hooking under a lug 79 on the base 60; and at the back the two parts can be hinged or have a suitable interlocking connection, but these parts are not shown in the drawing.

Various changes can be made in the details of construction and arrangement without departing from my invention.

What I claim as new and desire to secure by Letters Patent, is:

1. The combination with a carriage, escapement means normally restraining movement of said carriage, and a carriage releasing means for freeing said carriage from the restraint of said escapement means, of a part movable from a working position to a compacted position, said part being so related to said releasing means as that said

carriage is necessarily freed from the restraint of said escapement means when said part is compacted.

2. The combination with a carriage, escapement means normally restraining movement of said carriage, and carriage releasing means for freeing said carriage from the restraint of said escapement means, of a part movable from a working position to a compacted position, said part being so related to said releasing means as that said carriage is necessarily freed from the restraint of said escapement means when said part is compacted; and a lock to hold said carriage in proper position when the machine is compacted.

3. In a typewriting machine, the combination with a carriage and escapement mechanism therefor, of a part compactible to reduce the dimensions of the machine, and means effective to prevent the compacting of said part and operative to release the carriage, but ineffective to prevent the compacting of said part when the carriage is released by an operation of said means.

4. In a typewriting machine, the combination with a carriage and escapement mechanism therefor, of a part compactible to reduce the dimensions of the machine, means effective to prevent the compacting of said part and operative to release the carriage, but ineffective to prevent the compacting of the part when the carriage is released by an operation of said means, and a lock for locking the carriage in position for portability.

5. The combination with a case comprising a cover for enclosing a typewriting machine, of a machine including a part adapted to be compacted, said part being of such dimensions and occupying when in use such a position as to prevent the application of said cover but being movable to a compact position where the cover may be applied to the whole machine, a carriage, escapement means normally restraining movement of said carriage, carriage releasing means for freeing said carriage from the restraint of said escapement means, and a part movable from a working position to a compacted position, said part being so related to said releasing means as that said carriage is necessarily freed from the restraint of said escapement means when said part is compacted.

6. In a typewriting machine, the combination of a platen, a finger wheel therefor movable into compact relation to other parts, a carriage on which said platen is mounted, escapement mechanism, and a carriage release device so correlated with said finger wheel as to prevent the finger wheel from being pushed in unless the carriage is released.

7. In a typewriting machine, the com-

- bination of a platen, a finger wheel therefor movable into compact relation to other parts, a carriage on which said platen is mounted, escapement mechanism, and a 5 device forming a lock to keep said finger wheel in its outer position and operative to release the carriage, but ineffective to prevent movement of the finger wheel to its inner position when the carriage is released by an operation of said device. 10
8. In a typewriting machine, the combination of a platen, a finger wheel therefor movable into compact relation to other parts, a carriage on which said platen is mounted, escapement mechanism, a device 15 forming a lock to keep said finger wheel in its outer position and operative to release the carriage, but ineffective to prevent movement of the finger wheel to its inner position when the carriage is released by an operation of said device, and a lock for the carriage. 20
9. In a typewriting machine, the combination of a platen, a shaft connected with 25 said platen for turning the same and slideable in and out, a finger wheel on said shaft at one end thereof, a lever which when said finger wheel is drawn out overlaps the other end of said shaft to lock it in its extended position, carriage escapement mechanism, and a releasing connection between said lever and said carriage escapement mechanism. 30
10. The combination with a carrying case 35 and a typewriting machine adapted to be carried in said case and including a carriage and feed mechanism therefor, of means for compelling the freeing of the carriage from the restraint of said feed mechanisms to enable the machine to be enclosed in said case. 40
11. In a typewriting machine, the combination of a rotary platen having bearings
- in its ends, a shaft and supports therefor, the shaft being adapted to be inserted in said bearings, one end of said shaft and the bearing at that end being round and the shaft at the other end being flattened, and the bearing at said other end being correspondingly shaped, the construction being such 45 that the shaft can be inserted at that end where the bearing is round and that at the end of the flattened portion of the shaft is left a shoulder to limit the endwise motion of the shaft, and a finger wheel on said shaft, the entire construction being such 50 that said shaft can be slid in and out a limited distance and that said finger wheel can be used to turn the platen. 55
12. In a typewriting machine, the combination of a carriage having a platen, carriage escapement mechanism, normally restraining movement of the carriage, a finger wheel for said platen compactible with relation to said platen, and means whereby 60 said finger wheel cannot be compacted without the carriage is released from such restraining of its escapement mechanism. 65
13. In a typewriting machine, the combination with a spring-propelled carriage, 70 an escapement mechanism therefor comprising dogs and a toothed rack or member, carriage releasing means adapted to separate the said dogs and the said toothed rack or member, a part movable to compact the machine, said part being so related to the carriage release mechanism as that it cannot be compacted so long as the dogs and rack remain unseparated. 75
- Signed at Syracuse, in the county of 80
Onondaga and State of New York this 11th
day of October, A. D. 1919.
